RICHARD ZIESING, OF CLEVELAND, OHIO, ASSIGNOR OF ONE-HALF TO THE GRASSELLI CHEMICAL COMPANY, OF CLEVELAND, OHIO, A CORPORATION OF OHIO.

PROCESS OF REFINING ZINC.

No. 893,415.

Specification of Letters Patent.

Patented July 14, 1908.

Application filed February 27, 1907. Serial No. 359,607.

To all whom it may concern:

Be it known that I, RICHARD ZIESING, a citizen of the United States of America, and a resident of Cleveland, in the county of Cuyahoga and State of Ohio, have invented certain new and useful Improvements in Processes of Refining Zinc, of which the following is a specification.

My invention relates to improvements in processes of refining zinc and more particularly to the separation of zinc from such metals as lead and silver.

It has long been known that zinc may be separated from metals having greater specific gravity by reducing the spelter to a molten condition and allowing the heavier metal to settle out. The zinc, under these conditions, may be distilled at a temperature which will not affect the heavier metal, although in practice it is found that the process is frequently accompanied by the distillation of appreciable percentages of the contaminating metal or metals. The prior processes of separation have been carried on in the ordinary or slightly modified Belgian furnace and certain precautions, such as reversely inclining the retorts and cooling the same, have been resorted to in order to reduce the percentage of contaminating metal to as small an amount as was practicable. Due partly to the fact that the heat is applied from below to the retorts, and the lead or other contaminating metal is thereby frequently in a state of ebullition, the process of separating the zinc therefrom is one which must be carefully controlled by skilled employees, in order to secure satisfactory results, otherwise the percentage of contaminating metal may rise to an undesirable or prohibitive amount. In view of the conditions requisite for the satisfactory separation of these metals, I have devised an improved method and apparatus for practicing the process in question.

Briefly stated, the process consists in directing heat against the retorts or receptacles from above, and suitably shielding those portions of the retort containing the lead, silver and the like from any direct heat, whereby the body of contaminating metal remains quiescent, while the other portions of the retort are raised to a sufficiently high temperature to maintain rapid distillation of the zinc.

The preferred apparatus for practicing my improved process consists of a down-draft

furnace, wherein the retorts are disposed upon beds or supporting pillars of non-conducting material. Specially formed retorts adapted to retain the bottom portions of their contents in a relatively cool condition, may be employed in connection with my improved furnace.

Further details of the foregoing will be readily gathered by making reference to the accompanying drawings showing one means of practicing my invention, wherein,—

Figure I is a transverse sectional view through the furnace, a retort and condenser; the furnace bed being partially broken away in order to show the flue-connection. Fig. II is a longitudinal sectional view taken through one section or division of the furnace. Fig. III is a detail in longitudinal section of the flask and rearward portion of a self-sealing retort, and Fig. IV is an end view of a retort specially adapted for the process herein set forth.

Throughout each of the several figures of the drawings, I have employed the same character of reference to indicate similar parts.

In the drawings I have depicted one section of a small furnace embodying my improvements and adapted for the practice of my invention. Therein is shown a down-draft gas-fed furnace, wherein the distilling retorts *a* are carried upon a recessed perforated bed *b*; said recesses *b'* being adapted suitably to protect the bottoms of the retorts against the distilling heat maintained in the combustion chamber *c*. The perforations *b*² in said bed connect with sub-flues *d*, leading rearwardly to the main flue *e* connecting with the chimney-stack. Front and back buck-stays *f* support the furnace walls *c'*, and the dome *c*² of the combustion chamber, while upon the rear buck-stays are provided arms *f'* carrying the gas main *g*. Said main *g* is provided at intervals with intermediate connecting pipes *g'* and air-mixers *g*², opening within the combustion chamber.

Any suitable retort may be employed in my improved furnace, but preferably I use a retort generally oval in cross-section and provided with thickened bottom portions *a'*, as shown in Fig. IV. These heavy walls in association with the recesses *d'*, which may be backed with asbestos or other suitable material, serve to shield the bottom portions of the retort against any undue heating, and

protect the contained metal from relatively high temperatures. Thus all tendency toward ebullition of the metal is overcome, while the thinner upper walls of the retort 5 permit the penetration of heat from above to insure the surface distillation of the zinc.

Instead of the foregoing construction, I 10 may employ other retorts such as the ordinary types shown on the left-hand side of Fig. II, or those of the type set forth in my Patent No. 818,070, dated April 17th, 1906, wherein the thickened bottom walls are provided with an air shield or cushion, and may be cooled by the circulation of air adjacent 15 to the bottom portions.

15 The rear portion of the retort preferably is provided with an opening a^2 for charging in the spelter, which opening normally is sealed with a plug of fire clay a^3 . Or again, the opening a^4 may extend diagonally below the 20 normal level of the metal, as shown in Fig. III, thereby making the retort entirely self-sealing.

25 Luted into the forward end of the retort, is a suitable flask or condenser h , which preferably is provided with an interior rim h' adapted to retain the zinc from flowing back, as it is distilled over from the retort, and from which the zinc may be removed from 30 time to time. The condenser is readily removed from the retort whenever it becomes necessary to collect therefrom the accumulated lead, silver or other contaminating material.

35 My improved process may now be readily explained and understood, as practiced with the improved furnace above described. The combustion chamber being suitably heated from above, by means of the gas burners, and 40 the retorts being charged with spelter to approximately the level shown in the drawings. It will be appreciated that the lowermost portions of said retorts necessarily are shielded from the temperature of the combustion chamber, which preferably is just sufficient to insure the distillation of zinc. 45 This, of course, maintains the bodies of metal within the retorts in highly fluid condition, and permits the heavier contaminating metal, such as lead or silver, to sink 50 down to the lowermost portions or grooves a^5 of said retorts, where said metal remains quiescent. On the other hand, the surface temperature of the zinc is sufficient to cause 55 its rapid distillation in uncontaminated condition, into the forwardly positioned condensers. The heat being directed toward the top portions of the retorts wherein the distillation must necessarily take place, is subject 60 to very close regulation, particularly when the down-draft gas furnace of my invention is employed, and moreover the body of the retort containing the molten lead remains relatively cool, and is subjected in 65 lesser degree to the destructive action of that

metal. Under these conditions, the smallest fraction of a percent. of contaminating metal, will be found in the purer zinc collected in the condensers.

It will be appreciated that both the construction of my improved furnace, providing protective shields recessed to contain asbestos, ground fire-clay or other suitable material, and the construction of the specified retorts, mutually contribute to the success of the process as practiced, but either of these features may be independently employed in connection with suitable means for directing the distilling heat from above.

By reason of the fact that the retorts in 80 my improved furnace are supported throughout their entire length, as opposed to the usual support from front and rear walls of the furnace, it is possible to increase the length and diameter of the retorts indefinitely, which of itself serves to economize 85 space, fuel and labor. As thus disposed, the retorts are rendered self-sealing against minor perforations or leakage, since the metal flowing through such perforation will 90 come into contact with the relatively cooler body of the supporting shield, the fire-clay or asbestos and solidifying, seal such accidental opening. Where additional horizontal rows or tiers of the retorts are to be used, however, 95 it is preferable to employ retorts with heavy-heat resisting bottom portions, of the types herein referred to, supported from the front and rear in the usual manner and thus saving 100 the space otherwise required for separate shielding members.

The process as herein outlined, accomplishes economies in reduced costs of labor, in attending the furnace, and in minimizing the destructive action of the lead or other 105 metal upon the retorts, while permitting longer continuation of the process, by repeated charging of the retorts.

Having now described the preferred means and process contemplated by my invention, I 110 claim as new and desire to secure by Letters Patent, the following:

1. The herein described process of separating zinc from metals possessing greater specific gravity, consisting in directing heat 115 from above against the receptacle containing the zinc-alloy, sufficient to maintain the body of metal in a molten condition and insure surface-distillation of the zinc, substantially as set forth.

2. The herein described process of separating zinc from metals possessing greater specific gravity, consisting in directing heat against the receptacle containing the zinc-alloy sufficient to maintain the body of metal 125 in molten condition, while insuring the distillation of the zinc, and shielding from heat the portion of the receptacle wherein the metal of greater specific gravity collects, substantially as set forth.

3. The herein described process of refining zinc from an alloy containing lead, which consists in directing heat from above against the receptacle containing the zinc-lead alloy, sufficient to maintain the body of metal in a freely molten or fluid condition and meanwhile insure surface distillation of the zinc, whereby the lead settles to the bottom of the receptacle and the zinc is vaporized, and shielding the lower portion of the receptacle containing the lead from heat, substantially as set forth.

4. A method for separating zinc from metals of greater specific gravity, consisting

in charging the alloy into retorts, heating the 15 retorts from above to a temperature effecting surface distillation of the zinc, permitting the heavier metal to remain quiescent in a constricted portion of the retort, shielding such portion from excessive heat, and collecting 20 the zinc as it is distilled, substantially as set forth.

Signed at Clarksburg, W. Va., this 25th day of February, 1907.
